SELF-LOCKING PAPER BOX

Theodore L. Neumann, Dayton, Ohio

Application May 3, 1933, Serial No. 669,236

4 Claims. (Cl. 229—41)

This invention relates to new and useful improvements in self-locking paper boxes.

It is one of the principal objects of my invention to provide a paper box that may be instantly converted from a collapsed to a completely set up position in one operation, without touching the bottom, through pressure exerted upon two opposite corners of the box. The box being self locking, it may be set up in approximately one sixth 10 the time required for the old style of folding box.

Because of the speed with which it can be put in a material receiving state, the box lends itself admirably to those establishments where it is desired to pack different items such as various 15 kinds of candy in a segregated manner in a shipping case. It may also be used to great advantage for enclosing hats and kindred articles.

Other important and incidental objects will be brought out in the following specification, and particularly set forth in the subjoined claims.

In the accompanying drawing, Figure 1 is a plan view of a box blank constructed to achieve the objects of my invention. Figure 2 is a top view of the box partially open as a result of the 25 pressure applied to its opposite corners indicated by the arrows in that figure. Figure 3 is a top view of the box after it has been fully opened, and its bottom self-locked in its flat position, as a result of the continuation of pressure applied 30 to the opposite corners of the box. Figure 4 is a view of the bottom of the box in its self-locked state. And Figure 5 is a side view of the box with two sides broken away to show the box in its partially opened state.

In the accompanying drawing illustrating the form of embodiment of my invention therein disclosed, the numeral 1 designates a blank formed of a single piece of paper stock or other suitable material which is suitably cut and creased preliminary to being connected at its free ends. This blank has an elongated rectangular portion which is divided by transverse crease lines 2, 3, 4 and 5 into side walls 6, 6 and end walls 7, 7. Beyond the crease line 5 is a narrow flap portion 8 by which the outer end wall 7 is attached to the outer side wall 6 of the blank in a conventional manner.

Referring to Figure 1, each side wall 6 is provided, beyond a crease line 9 parallel with the outer longitudinal edge 10 of the blank, with a bottom flap 11 that has a foot-shaped locking terminal portion 12. As illustrated in Figure 1, one side edge 13 of each bottom flap 11 has an irregularly curved contour, while its opposite 55 edge 14 inclines in a straight line to a right-

angled recessed part 15 that defines the heel portion of the locking terminal 12.

Beyond the crease line 9 each end wall 7 is provided with a bottom flap 16, one side edge 17 of which is a straight line continuation of the transverse crease line. The opposite side edge 18 is a straight continuation of the transverse crease line to a point a short distance below the crease line 9, whence it inclines inwardly to a point a short distance to the left of a middle 10 recess 19 formed in the outer portion of the flap. Each recess 19 has opposite curved edges and a straight edge portion. A straight crease line 20 leads from the meeting point of the straight and curved portions of the recess to the meeting point 15 of the transverse and longitudinal score lines, at the left of the recess. The portion of each bottom flap 16 outside the crease line 20, constitutes a hinged flap 21 for connecting each bottom flap 16 to the edge portion 14 of its adjacent bottom 20 flap 11 in a conventional manner when the outer side wall portion 6 of the blank is secured to the outer end wall portion 7 of the blank by the hinged flap 8.

After the above end, side wall and bottom flap 25 connections have been made, the box is in a collapsed state from which it may be almost instantly brought to a completely open or set up position by exerting pressure against two of its opposite corners, as, for example, those designated 30 by the arrows in Figure 2.

In their collapsed state the two pairs of connected bottom flaps, hinged along the score lines 20, 20 respectively, lie flat against the inner surfaces of the connected side and end walls of 35 the box, with the locking terminals 12, 12 in their extended positions. When pressure is exerted against the opposite corners designated by the arrows in Figure 2, the walls of the box approach a right-angled relationship with each other as 40 the two bottom flap sections move outwardly into a horizontal plane. During the outward movement of these bottom flap sections, the outer ends of the locking terminals 12 on the flaps 11 automatically enter the recesses 19 in the flaps 16 45 as illustrated in Figures 2 and 5. Now, when the box has been fully opened, the recessed portions 22 formed by the opposite curved edges in the flaps 11, 11, engage the inner ends of the recesses 19, while the heel portions of the terminals 12 50 engage each other, to firmly lock the box in its open position. (See Figures 3 and 4). Not only is the box self-locking, but the bottom flaps are locked at several points to effect a firm connection of them.

It is thus seen that I have provided a paper box for candy, hats or other articles, which can be fully opened from a collapsed position to receive them, by pressure exerted against two opposite corners of the box without touching its bottom at all.

Having described my invention, I claim:

1. A self-locking box comprising hingedly connected side and end walls adapted to be brought from a collapsed state to a full open position by pressure against two opposite corners of the connected walls, folding bottom sections for said box, integral with its side and end walls, alternate bottom sections formed with recessed edges, and foot-shaped locking tongues on the remaining bottom sections for entrance into said recesses, and also for engagement with each other at their heel portions, when the box is fully opened, to firmly hold it in said position with its bottom securely closed.
2. A self-locking box comprising hingedly connected side and end walls adapted to be brought from a collapsed state to a full open position by pressure against two opposite corners of the connected walls, bottom flaps hingedly secured to the end and side walls, the bottom flaps of the end walls being formed with recesses in their outer edges, locking terminals on the outer portions of the bottom flaps on the side walls, the bottom flaps on the end walls being hingedly secured to the adjacent bottom flaps on the side walls to provide two bottom flap sections, each adapted to fold upon itself against the inner surface of the side and end walls when the box is in a collapsed state, and the locking terminals on the bottom sections adapted to automatically enter the recesses in the edges of the adjacent bottom sections, and also to engage each other, when

the box is fully opened to firmly hold it in said position with the bottom securely closed.

3. A self-locking box comprising hingedly connected side and end walls adapted to be brought from a collapsed state to a full open position by pressure against two opposite corners of the connected walls, a bottom flap hingedly secured to each one of said walls, the bottom flaps on the end walls being formed in their outer edges with recesses, foot-shaped terminals on the outer portions of the bottom flaps of the side walls, the bottom flaps on the end walls being hingedly secured to the adjacent bottom flaps on the side walls to provide two bottom flap sections, each adapted to fold upon itself against the inner surface of the side and end walls when the box is in a collapsed state, and the foot-shaped terminals on the bottom sections adapted to automatically pass each other and enter the recesses in the adjacent bottom sections when the box is fully opened to firmly hold it in said position with the bottom securely closed.

4. A self-locking box comprising hingedly connected side and end walls adapted to be brought from a collapsed state to a full open position by pressure against two opposite corners of the connected walls, folding bottom sections for said box, integral with its side and end walls said end walls being hinged to the side walls, alternate bottom sections formed with recessed edges, locking tongues on the remaining bottom sections for automatic locking entrance into said recesses when the box is pressed to an open position, and projections on the recessed edges of the alternate bottom sections to lie under the said tongues to reinforce the box bottom when the box is fully opened.

THEODORE L. NEUMANN.
